UNITED STATES PATENT OFFICE.

HENRY D. POWNALL, OF CINCINNATI, OHIO.

ICE-MACHINE.

964,936.

Specification of Letters Patent. Patented July 19, 1910.

Application filed May 18, 1908. Serial No. 433,522.

To all whom it may concern:

Be it known that I, HENRY D. POWNALL, citizen of the United States, residing at Cincinnati, in the county of Hamilton and 5 State of Ohio, have invented certain new and useful Improvements in Ice-Machines, of which the following is a specification.

My invention relates to improvements in ice and refrigerating machinery. 10 One of its objects is to provide improved mechanism and arrangement of parts for cooling and circulating the brine.

Another object is to simplify the brine cooling and gas expansion mechanism, and 15 to reduce the quantity of expansion pipe or surface required.

Another object is to provide a mechanism which can be assembled in the factory instead of being erected at the place where it 20 is to be used.

Another object is to secure a minimum frictional resistance to the refrigerant during expansion, and to prevent the formation of pockets of oil or other obstructions to the 25 circulation of the refrigerant.

Another object is to prevent the passage of vaporous or liquid refrigerant to the off- take pipes.

Another object is to avoid the use of expansion coils in close proximity to the ice cans.

Another object is to provide mechanism more readily accessible for repairs.

Another object is to provide improved mechanism for separating and removing oil, water and other impurities from the refrigerant in the expansion mechanism.

Another object is to provide improved mechanism for automatically controlling the 40 supply of refrigerant to the expansion mechanism.

It further consists in certain details of form, combination and arrangement, all of which will be more fully set forth in the 45 description of the accompanying drawings, in which:

Figure 1 is a horizontal section on line v v of Fig. 2, through a brine tank and brine cooling and circulating mechanism embodying my improvements. Fig. 2 is a vertical section on line z z of Fig. 1, also disclosing in central vertical section the mechanism for separating impurities. Fig. 3 is a view simi-

lar to Fig. 1 of a modification. Fig. 4 is a vertical section through a modification of the 55 brine cooling mechanism. Figs. 5 and 6 are plan views of brine tanks and cooling and circulating mechanism illustrating modifications of Fig. 1. Fig. 7 is a vertical section through the gas expanding and brine cooling 60 mechanism, and mechanism for automatically feeding the refrigerant thereto. Fig. 8 is a perspective view of a section of one of the brine cooling pipes. Fig. 9 is a section on line w w of Fig. 8. 65

In the accompanying drawings Figs. 1 and 2 represent the preferred form of mechanism for cooling and circulating the brine.

A represents a metal tank and A' an insulating covering for the exterior thereof. 70 The tank A is subdivided by partitions a a' a^2 a^3 into separate compartments a^4 a^5 a^6 a^7 a^8 . When used for the manufacture of ice, the compartments a^4 a^5 are filled with cans a^9 of fresh water to be frozen, which cans are 75 surrounded with cold brine. The partition a^3 is perforated, and the compartment a^6 serves as a passage way for the brine from compartment a^4 to compartment a^5 .

B represents a sheet metal tank or drum, 80 preferably cylindrical with heads b at opposite ends, and preferably a hood b' at one or both ends.

b^2 represents tubes passing through drum B from end to end and secured tightly at 85 opposite ends to the heads b . The drum B passes through the partition a^2 , or abuts an opening therein, so that the brine is free to pass through the tubes b^2 from compartment a^7 to compartment a^8 . 90

C represents a brine circulator, preferably a propeller having blades c and journaled in sleeve c' and journal box c^2 .

c^3 represents a tight and c^4 a loose pulley by means of which and a belt the propeller 95 is rotated or stopped as desired. When the propeller is rotated its blades cause a circulation of the brine from compartment a^7 through the tubes b^2 to compartment a^8 from whence it flows through perforations 100 a^{10} in the partition a' , the perforations a^{10} being preferably located opposite the spaces between the ice cans, and thence into compartment a^4 where the brine circulates around and between the various ice cans and 105 from compartment a^4 enters compartment a^6 .

through perforations a^{11} in partition a^3 . From compartment a^8 the brine flows through perforations a^{12} in partition a^3 into compartment a^5 and around the ice cans therein. From compartment a^5 the brine is returned to compartment a^7 through perforations a^{13} in the partition a^7 .

The drum B is maintained nearly full of liquefied gas which is supplied by means of a 10 valve-controlled supply pipe b^3 . A liquid gage b^4 serves to indicate to the operator the height of the liquefied gas in drum B. An off-take or suction pipe b^5 leads from the top of drum B to the ice machine compressor or 15 absorber to conduct away from drum B the refrigerating gas as soon as it has assumed the gaseous state and transferred its negative heat to the brine circulating through the tubes b^2 . By this arrangement the inner 20 wall of drum B and practically all of the tubes b^2 are in direct contact with liquid gas upon one side and in contact with the brine to be cooled upon the other side, thus producing a device of compact form and great 25 efficiency per unit surface employed; also by submerging the drum B in the brine in compartments a^7 a^8 , the exterior of the drum becomes an active surface, and no insulating material is required upon the exterior of the 30 drum. Also the parts are all subjected to a uniform temperature and expand and contract in unison. The drum B and its contained parts can be readily assembled and tested at the factory, and are conveniently 35 accessible for repairs. Where large brine tanks are required, two or more drums B may be employed in connection with the one brine tank as indicated in Figs. 5 and 6. The circulator or propeller may be variously located 40 relative to the tank and drum B or brine cooling member, so long as it serves to create a circulation of brine through the tank and thence over the face of the brine cooling member.

45 In order to purify the liquefied gas and separate therefrom the oil, water, and other impurities which tend to accumulate in the lower part of drum B, I provide a pipe E leading downward from drum B and into 50 a closed chamber e , pipe E being controlled by a valve e' .

55 F represents a pipe tapping the upper portion of chamber e , controlled by a valve f and connected at the opposite end to suction pipe b^6 .

G represents a tank in which chamber e is located and adapted to be immersed in a heating medium such as steam or hot water, preferably hot water.

60 g represents a supply pipe for the heating medium, and g' an overflow pipe for the same.

f' represents a pipe through which the impurities may be discharged from chamber e 65 into a receiver f^2 .

In practice, when it becomes desirable to withdraw impurities, a quantity of the contents of drum B is drawn off into chamber e until chamber e is half to two-thirds full, then valve e' is closed, heat is applied to 70 chamber e and valve f opened, when the liquefied gas will vaporize and pass off through pipe F, leaving the impurities in chamber e , from which they may be withdrawn.

In the modification Fig. 3 the drum B' instead of being immersed in the brine in a compartment of the brine tank, is located at one end thereof and is connected to the brine tank at opposite ends by means of 75 metal head pieces H H' clamped to the ends of drum B' and provided with passages h h' leading the brine to and from drum B'. The propeller h^3 is mounted upon the head h^4 . Drum B' may if desired, where space is 80 limited, be located either above or below the end of the brine tank instead of at the end as shown in Fig. 3. Drum B' is provided with a non-conducting covering h^5 .

In Fig. 7 I have shown means to automatically regulate the flow of liquefied gas to the drum B, thus uniformly maintaining the liquefied gas therein at the desired height. I represents a chamber at one side of which is a valve i which is controlled by 90 the movements of a float i' . A pipe J connects the lower portion of chamber I with the lower portion of drum B, while pipe K connects the upper portion of chamber I with the suction pipe or upper portion of 95 drum B, so that the liquefied gas assumes the same level in chamber I as in drum B, and whenever the level of liquefied gas falls the float i' opens valve i and admits more 100 liquefied gas from the pipe k which supplies the liquefied gas, and which then flows through pipe k' controlled by valve k^2 and enters pipe J. k^3 represents a by-pass pipe controlled by valve k^4 , through which liquefied gas can be supplied to drum B in the 105 event that valve i should fail to operate from any cause. k^5 represents the liquid gage to indicate the height of the liquefied 110 gas in drum B. The chamber I and connecting pipes may be submerged in the 115 brine by the side of drum B if desired.

In constructing the drums B B' I preferably employ tubes of the character indicated in Figs. 8 and 9, that is tubes having cylindrical ends and a spiral or corrugated 120 instead of cylindrical middle section. Tubes of this character are more flexible endwise, and are thus less liable to injure the joints where the ends of the tubes are united to the heads of the drum. They also impart a 125 spiral movement to the brine flowing through the tubes and thus greatly increase the efficiency of the device per unit area exposed.

In Fig. 4 I have shown a modification of 130

the brine cooling member to be employed in place of drum B, and which is less expensive at first cost than drum B. L represents a series of horizontal pipes located in a compartment l corresponding to compartments a' a'' of Fig. 1, of the brine tank and separated from the ice can compartment by a partition corresponding to partition a' of Fig. 1. M represents a header located at the bottom and at one end of compartment l, and connected to one end of the respective pipes L by means of pipes m, preferably of smaller diameter than pipes L. M' represents a header at the opposite end of compartment l near the top, and which is connected to the opposite end of pipes L by pipes m', also preferably of smaller diameter than pipes L. Two or more sets of pipes L and headers M M' are preferably arranged side by side in compartment l, and connected together by a header N to which the liquefied gas supply pipe n is connected, which header N is connected to each header M by a pipe n' and to each header M' by a pipe n''. P represents a liquid gage to indicate the height of liquefied gas in the pipes L. In operation the liquefied gas is supplied so as to fill all the pipes L, but not the headers M'. The vaporized gas from pipes L m and headers M rises through pipes m' to headers M' from whence it is withdrawn by the compressor through suction pipes m'' which all unite in a header m''. Any liquid which may be forced into headers M' returns to header N by pipes n''. The brine is admitted to compartment l through an opening p² in the partition p and after circulating over pipes L is forced from compartment l by propeller through opening p³ in partition a'. The shape of the piping of Fig. 4 is such as to permit considerable expansion and contraction without injury to the joints.

The mechanism herein illustrated and described is capable of considerable modification without departing from the principle of my invention.

Having described my invention, what I claim is:

1. In a mechanism of the character described, a brine tank divided by a partition to cause the brine to flow in a loop-shaped path, means to circulate said brine, a brine cooling member in contact with the circulating brine, said member comprising an expansion chamber adapted to hold a body of liquefied gas in a state of substantial equilibrium, a liquefied gas supply pipe connected to said chamber, an off-take pipe connected to said chamber above said body of liquefied gas to convey from said chamber the gaseous products arising from said liquefied gas, and means to withdraw from said cooling member the accumulating impurities.
2. In a mechanism of the character de-

scribed, a brine tank divided by a partition to cause the brine to flow in a loop-shaped path, means to circulate said brine, a brine cooling member in contact with the circulating brine, said member comprising an expansion chamber adapted to hold a body of liquefied gas in a state of substantial equilibrium, a liquefied gas supply pipe connected to said chamber to supply liquefied gas thereto, an off-take pipe connected to said chamber above said body of liquefied gas to convey from said chamber the gaseous products arising from said liquefied gas, and a gas purifying member adapted to separate the impurities accumulating in said cooling member from the liquefied gas contained therein.

3. In a mechanism of the character described, a brine tank, a partition therein to cause the brine to flow in a loop-shaped path in said tank, means to circulate the brine in said tank, a brine cooling member comprising an outer shell spanned by a series of tubes, said shell forming a chamber to contain a body of liquefied gas in substantially a state of equilibrium, and said tubes being immersed in the liquefied gas and forming passages for the circulating brine, a valve controlled pipe to supply liquefied gas to said chamber, an off-take pipe tapping said chamber above the level of the liquefied gas to convey from said chamber the gaseous products arising from said liquid, and means to remove from said brine cooling member a portion of the cooled liquefied gas together with the impurities accumulated therein.

4. In a mechanism of the character described, a brine tank divided by a partition to cause the brine to flow in a loop-shaped path, means to circulate said brine, a brine cooling member in contact with the circulating brine, said member comprising an expansion chamber adapted to hold a body of liquefied gas in a state of substantial equilibrium, a liquefied gas supply pipe connected to said chamber to supply liquefied gas thereto, an off-take pipe connected to said chamber above said body of liquefied gas to convey from said chamber the gaseous products arising from said liquefied gas, and a gas purifying member adapted to periodically remove the impurities accumulating in said cooling member.

5. In a mechanism of the character described, a brine tank divided by a partition to cause the brine to flow in a loop-shaped path, means to circulate the brine, a brine cooling member in contact with the circulating brine, said member comprising an expansion chamber adapted to hold a body of liquefied gas in a state of substantial equilibrium, a liquefied gas supply pipe connected to said chamber to supply liquefied gas thereto, an off-take pipe connected to said chamber above said body of liquefied gas to convey from said chamber the gaseous products arising from said liquefied gas, and a gas purifying member adapted to periodically remove the impurities accumulating in said cooling member.

gas to convey from said chamber the gaseous products arising from said liquefied gas, and a gas purifying member adapted to withdraw a portion of the cooled liquefied 5 gas together with the accumulated impurities from said cooling member, and to separate the withdrawn gas from said impurities.

In testimony whereof I have affixed my signature in presence of two witnesses.

HENRY D. POWNALL
